UNITED STATES PATENT OFFICE.

WILLIAM ANDREW HARRIS, OF GREENVILLE, SOUTH CAROLINA, ASSIGNOR TO
AUTOMATIC PUMP CORPORATION, OF NORFOLK, VIRGINIA, A CORPORATION
OF VIRGINIA.

AUTOMATIC PUMP.

1,242,548.

Specification of Letters Patent.

Patented Oct. 9, 1917.

Application filed May 20, 1916. Serial No. 98,748.

To all whom it may concern:

Be it known that I, WILLIAM A. HARRIS, a citizen of the United States, and a resident of Greenville, in the county of Greenville and State of South Carolina, have invented a certain new and useful Improvement in Automatic Pumps, of which the following is a specification.

My invention relates to improvements in automatic pumps, especially those that are designed to be operated by compressed air, and it consists in the combinations, constructions, and arrangements herein described and claimed.

15 An object of my invention is to provide an improvement in that form of automatic pump disclosed in my prior Patent Number 1,053,032, of February 11, 1913, the said improvements consisting, first, in providing 20 new features which prevent the binding of certain of the parts, second, in providing an arrangement by which air cannot get in on top of the piston to oppose the movement of the air underneath the piston, and third in 25 providing a valve which will prevent the leakage of air.

Other objects and advantages will appear in the following specification, and the novel features of the invention will be particularly pointed out in the appended claims.

30 My invention is illustrated in the accompanying drawings forming part of this application, in which:

Figure 1 is a side view of the device.

35 Fig. 2 is a vertical sectional view through the air cylinder, valve, and diaphragm, showing the valve in one position.

Fig. 3 is a sectional view showing the 40 valve in another position.

Fig. 4 is a side view of the upper portion of the apparatus.

Fig. 5 is a section along the line 5—5 of Fig. 4.

Fig. 6 is a top plan view of the diaphragm 45 casing.

Fig. 7 is a section along the line 7—7 of Fig. 3.

Fig. 8 is a sectional view of a portion of the pressure-controlled valve.

50 Fig. 9 is an enlarged section through the diaphragm.

Fig. 10 is a section on the line 10—10 of Fig. 4.

In carrying out my invention I provide

a base 1 upon which is a standard 2. The 55 base is designed to rest upon the top 4 of a well 5 in which the pump cylinder 6 is disposed. At the top of the standard 2 is secured the air cylinder 7. The latter is provided with a piston 8 whose piston rod 9 60 passes through a stuffing gland 10 in the bottom of the cylinder, thence downwardly into the pipe 11 which communicates with the pump cylinder 6. Secured to the piston rod 9 is an arm 12 to which is secured a vertical rod 13 passing through guides 13^a carried by the cylinder 7. At 14 I have shown a Z-shaped contact member which is secured to the rod 13 and which moves with it. At the top of the rod 13 is an arm 15. 70

Surmounting the cylinder 7 is a valve casing V, through the center of which extends a shaft 16 which is provided with an enlarged hub 17 bearing integral arms 17^a and 17^b, between the ends of which is loosely 75 disposed a valve 18 having a convex surface arranged to engage the interior of the valve casing V. The valve 18 is held in frictional engagement by means of a spring 19 which extends through the enlarged portion 17 and 80 into a housing 20 which forms an integral part of the enlargement 17. The valve casing V is provided at its bottom with a port 21 leading to a threaded bore 22, see Figs. 2 and 3. At the opposite side of the valve 85 casing is a threaded bore 23, which communicates with the interior of the cylinder 7, and permits free passage of air into or out of the portion of the cylinder 7 above the piston 8.

90 A pressure controlled valve of particular design is used in connection with the automatic pump. As will be seen from Fig. 2, this comprises a base portion 24 having a threaded extension 24^a arranged to enter a 95 threaded opening in the top of the valve casing V. The base portion is provided with a bore 25 which is threaded at its outer end. Communicating with the bore 25 is a vertical bore 26, and at the junction of the two 100 bores is a valve seat 27. A valve stem 28 is disposed with its axis in vertical alignment with the opening 26. This valve stem passes through a stuffing box 29 and extends 105 into the bore 25. The lower end of the valve stem 28 has a recess in which is disposed a spiral spring 30, see Fig. 8. A plunger stem 31 extends into the recess and bears on the

spring. This plunger stem is provided with a guide pin 32 arranged to slide in a slot 33. The head 34 connected to the plunger stem 31 bears on the seat 27.

5 A frame 35 is screwed to that portion of the base 24 which constitutes the stuffing box, and between the upper part of the frame and a cap 36 is arranged a diaphragm 37. This diaphragm is connected to the 10 valve stem 28, in the manner clearly shown in Fig. 9. It will be observed that a threaded extension 40 may be connected with the source of air which may press upon the top of the diaphragm. A nut 41 is disposed within the frame so as to screw up and tighten the packing around the stem 28. A spring 42 bears at one end on a nut 43 carried by the stem, and at the other end on a nut 41. The tension of the spring 42 15 may be changed by means of the nut 43.

20 Referring now particularly to Fig. 10, it will be seen that there is a cylindrical extension *v* of the valve casing V. The shaft 16 passes through this extension. A sleeve 16 is loosely mounted on the cylindrical extension *v*. One end of the sleeve bears 25 an arm 46 bearing a pin 47 to which is attached one end of a spring 48, the opposite end of the spring being attached at 49 to one 30 of the stay rods 50 which hold the head of the cylinder 7. The arm bears a pin 53 arranged to engage lugs 54 and 55 carried by a split collar 56 secured to the end of the shaft 16.

35 Considering now Fig. 1, it will be observed that the diaphragm casing communicates by means of a pipe 57 with an air chamber 58, the latter being in connection with a pipe 59 which has communication 40 with the pipe 11 leading to the pump cylinder. The pipe 59 may bear one or more faucets 60 which may be located in any convenient position, as in the bath room or kitchen of the building, or any place where 45 needed.

The compressed air tank is shown at T and may be of any suitable type. It is connected by means of a pipe 61 with the inlet 25 between the diaphragm and the valve 50 casing V.

From the foregoing description of the various parts of the device, the operation thereof may be readily understood.

The air is supplied by means of the tank 55 T or in any other suitable manner. Let us assume that the piston 8 is in the position shown in Fig. 2. Air from the tank T passes through the pipe 61 and thence past the valve member 34 through the inlet 26 60 into the valve casing through the port 21 and out through 22 and by means of a pipe 65, see Fig. 1, into the port 66 at the bottom of the cylinder, see Fig. 2, thereby forcing the piston 8 upwardly and carrying with it 65 the rod 13 which is secured to the piston

stem 9 and the arm 14 which is carried by the rod 13. Before the piston 8 reaches the top of its stroke, the arm 14 has engaged a roller 67 carried by an arm 68 which is secured to the sleeve 45, see Figs. 1, 2, 70 and 10. As the piston 8 continues to rise, the arm 14, see Fig. 4, will raise the arm 68 in the direction indicated by the arrow in Fig. 4, thus turning the sleeve 45 and with it the arm 46. As the latter turns the 75 tension of the spring 48 is increased, and when the arm 46 passes the vertical line through its pivotal support and the point 49 where the spring is secured, it will be suddenly shifted, due to the contraction of 80 the spring, and the engagement of the pin 53 with the lug 54 will cause a sudden throw of the valve from the position shown in Fig. 2 to that shown in Fig. 3, in which the valve 18 covers the port 21. The stop members 70 and 71 limit the throw of the valve 85 18, while lugs 51 and 52 limit the movement of the arm 68.

The upward movement of the rod 13 causes the stretching of a spring 72 which 90 is fastened to the base 1 and to an arm 13* carried by the rod 13. The shifting of the valve 18 from the position shown in Fig. 2 to that shown in Fig. 3 brings the exhaust port 73 into communication with the port 95 21, so that the piston 8 now has the tension of the spring 72 pulling it downwardly and the air underneath it in the cylinder in communication with the exhaust port. This moves the piston downwardly. 100

As the rod 13 moves downwardly the arm 15 engages the roller 67 on the arm 68 and moves the arm downwardly. This rotates the sleeve 25 and stretches the spring 48 as before, but when the arm 46 to which 105 the spring 40 is attached goes past its central position, it will suddenly be thrown forwardly so that the pin 53 engages the lug 55, see Fig. 4, thereby causing a quick throw of the valve from the position shown in Fig. 3 to that shown in Fig. 2. 110

The operations thus described are repeated, and the pump is operated by the air pressure. As the water is lifted, the air in the air chamber 58 and the pipe 57 115 is compressed, and when a predetermined pressure is reached the diaphragm 37 is forced downwardly against the tension of the spring 42 thus closing the valve 34 by seating it on the seat 27 and shutting off the supply of air. The pump will then stop. 120

If now water is drawn out of the faucet 60, the pressure in the air chamber 58 is relieved. The diaphragm resumes its original position under the action of the spring 42, 125 the valve 34 is lifted from its seat 27, compressed air enters the valve casing V, thus automatically starting the device.

It will be seen that the mere opening of the faucet and the drawing of the water will 130

cause the pump to operate automatically, and stop automatically when the pressure is sufficient to operate the diaphragm.

I desire to call particular attention to the 5 valve which controls the supply of air to the valve casing V, and which is operated by the diaphragm 37. As will be seen from Fig. 8, the valve member 34 is pressed on by the spring 30. A slight variation of pressure 10 and a corresponding movement of the diaphragm 37 will not open the valve because of the fact that the member 28 may have play, due to the slot and pin arrangement as shown in Fig. 8. When, however, there is a 15 considerable decrease of pressure, then the movement of the diaphragm is sufficient to withdraw the member 34 from its seat 27 and thereby permit the flow of air into the valve casing. In devices of this kind, it is 20 sometimes hard to prevent a slight fluctuation of pressure. With the device as arranged in Fig. 8, this slight variation of pressure is taken care of, and thus the pump will operate efficiently, where with a posi- 25 tively operated valve which moves under the slightest pressure, enough air may be admitted to interfere with the proper operation of the pump. One of the novel features 30 of the device lies in providing a valve which will not open under slight variations of pressure, but which will open instantly under a variation caused by the opening of a faucet.

I claim:—

35 1. In an automatic pumping device, a cylinder provided with an inlet for motive fluid at one end of the cylinder, a main valve for controlling the passage of the motive fluid through said inlet, a valve casing for said 40 valve, a pressure tank, a valve for controlling the entrance of motive fluid into said valve casing, a diaphragm connected to said last named valve and being exposed to the pressure from said pressure tank, and means 45 carried by the valve for holding the latter on its seat during slight movements of the diaphragm and arranged to open at a more extensive movement.

2. In an automatic pump, a cylinder, a valve casing carried by the cylinder, a fluid 50 pressure control valve for controlling the entrance of motive fluid into said valve casing, connections between said valve casing and one end of said cylinder, a rotatable shaft extending through said valve casing, a 55 valve within the valve casing adapted to be shifted by the rotation of said shaft for controlling the connections between the valve casing and the cylinder, an arm loosely mounted on the valve shaft, a stop member 60 arranged to be engaged by the arm, a piston within the cylinder, a piston rod, an auxiliary rod secured to said piston rod and 65 arranged for movement outside of the cylinder, a pair of arms carried by said auxiliary rod and arranged to engage the arm on said valve shaft for moving the latter, and a spring rigidly secured at one end and at the other end to said auxiliary rod and adapted to be placed under tension during 70 upward stroke of the piston, and means carried by said fluid pressure control valve for holding the latter on its seat during slight variations of pressure, said valve being arranged to be operated on greater variations. 75

3. A fluid pressure control valve comprising a casing, a diaphragm carried by the casing, means for admitting fluid pressure on one side of said diaphragm, a valve stem secured to said diaphragm, a spring for returning the diaphragm to its original position, a spring pressed head carried by the 80 valve stem, said head having a slight play, and a valve seat for said head.

4. A fluid pressure control valve comprising a casing, a diaphragm carried by the casing, means for admitting fluid pressure on one side of said diaphragm, a valve stem secured to said diaphragm, a spring for returning the diaphragm to its original position, a movable head carried by said valve stem, a spring for normally extending said head, and a pin carried by said head and arranged to play in a slot in said stem. 85 90

WILLIAM ANDREW HARRIS.
